UNITED STATES PATENT OFFICE.

PHILIP BADIS, OF CHICAGO, ILLINOIS.

DESIGN FOR A LADY'S HAND BAG.

Application filed June 25, 1925. Serial No. 13,887. Term of patent 7 years.

To all whom it may concern:

Be it known that I, PHILIP BADIS, a citizen of the United States, residing at Chicago, in the county of Cook and State of Illinois, have invented a new, original, and ornamental Design for Ladies' Hand Bags, drawing, forming part thereof.

The drawing shows the hand bag in perspective.

I claim:

The ornamental design for a lady's hand bag, as shown.

In testimony whereof I affix my signature in the presence of two witnesses at 10 South La Salle Street, Chicago, Illinois.

PHILIP BADIS.
